George Wetlaufer INVENTOR

BY

Geo. B. Willcox ATTORNEY

UNITED STATES PATENT OFFICE.

GEORGE WETTLAUFER, OF SAGINAW, MICHIGAN.

STACKER.

1,355,632.

Specification of Letters Patent.

Patented Oct. 12, 1920.

Application filed October 22, 1919. Serial No. 332,470.

To all whom it may concern:

Be it known that I, GEORGE WETTLAUFER, a citizen of the United States, residing at Saginaw, in the county of Saginaw and State of Michigan, have invented certain new and useful Improvements in Stackers; and I do hereby declare the following to be a full, clear, and exact description of the invention, such as will enable others skilled 10 in the art to which it appertains to make and use the same.

This invention relates to pneumatic stackers and pertains more particularly to that type of pneumatic stacker which comprises 15 an elbow that connects the air blast of a separating machine with a delivery pipe which terminates in a discharge pipe having an inner and outer telescoping section, adapted to be projected or retracted with respect to said inner section, to increase or 20 decrease the effective length of the discharge pipe.

It has been customary in pneumatic stackers of this type to hinge the discharge pipe 25 to the delivery pipe to enable it to swing horizontally so that the direction of the discharge in convenient places, such as barns or storage sheds, can be varied at will, but heretofore it has been customary 30 to adjust the length of the telescoping discharge pipe either by moving its outer section by hand, or to effect this lengthwise adjustment by means of chains or cables operating on pulleys, the chains being arranged 35 so that the discharge pipe could be extended or telescoped when the hinge was closed, but it has been necessary heretofore to remove or disconnect the chain when it was desired to open the hinge and thereby fold 40 the discharge pipe back upon the delivery pipe.

It is the object of my present invention to provide a simple and inexpensive means whereby the outer section of the discharge 45 pipe may be extended or retracted, and the hinge may be bent to fold the discharge pipe back upon the delivery pipe without disorganizing the means by which the telescoping section is actuated.

With these and certain other objects in view which will appear later in the specification, my invention comprises the devices described and claimed and the equivalents thereof.

In the drawings, Figure 1 is a side view

broken away in part, showing a stacker with my improvement attached.

Fig. 2 is an enlarged side view, partly in section, of the hinged end of the discharge pipe, the hinge being shown as it appears 60 when open.

Fig. 3 is a top plan view showing the hinged sections assembled and indicating by dotted lines the position of the delivery pipe when the hinge is open. 65

As is clearly shown in the drawings, 1 indicates the frame of a grain separator, 2 the usual elbow of a pneumatic stacker, terminating in a delivery pipe 3.

4 is the inner section of the discharge pipe 70 and 5 is the outer section of the discharge pipe arranged in sliding relation thereto.

The delivery pipe 3 is usually provided with a hinge member 6 and upon section 4 of the discharge pipe is the corresponding 75 hinge member 7, the two members enabling the pipes 3 and 4 to be opened and closed with respect to each other, as indicated by the dotted lines in Fig. 3.

In applying my improved device for telescoping the sections 4 and 5, I mount on delivery pipe 3 and preferably on the hinge member 6 carried thereby, a driving gear 8, and on the inner section of the discharge pipe 4, preferably on hinge member 7 carried thereby I mount a driven gear 9 in such manner that when the hinge is closed, as shown in Fig. 1 and in full lines in Fig. 3 the two gears 8 and 9 intermesh and when the sections are opened, as shown in Fig. 90 85 2 and by dotted lines in Fig. 3 the gears are out of mesh.

I prefer to provide suitable means for revolving the gear 8, as for example the chain 10, sprocket 11 and hand crank 12, 95 or the gear 8 may be actuated if desired by a crank connected directly to it, or in any other suitable manner.

I also connect the driven gear 9 with the outer telescoping section 5 of the discharge 100 pipe by any suitable operating means whereby the section 5 will be projected or retracted when the driven gear 9 is rotated by the driving gear 8.

As one improved means for operatively 105 connecting the gear 9 with the outer section 5 of the discharge pipe, I provide a supporting arm 13, which may be carried by the hinged member 7 and extends lengthwise the telescoping pipes 4 and 5. The 110

outer end of the arm 13 carries a sprocket 14, on which the chain 15 runs. To operate the chains 10 and 15 I prefer to provide on the gears 8 and 9 respectively sprockets 16 and 17.

- When crank 12 is operated, the hinge being closed as shown in Fig. 1, the driving gear 8 and the driven gear 9 are rotated, thereby moving the chain 15 so as to either 10 project or retract the outer section 5 of the discharge pipe. The chain 15 is preferably secured to section 5 by means of a lug 18 fixed to a band 19 carried by the outer section 5 of the discharge pipe.
15. By the means above described I have produced a simple, yet strong and efficient device whereby the outer telescoping section of a hinged stacker may be actuated when the stacker is closed and when the outer sections 20 of the stacker are opened by means of the hinge, the telescoping device will be temporarily disconnected and by means of the gears 8 and 9 will be automatically connected again and put in operative position 25 when the hinge is closed.

Having thus described my invention, what I claim and desire to secure by Letters Patent is:

1. In a pneumatic stacker comprising a 30 delivery pipe, a discharge pipe having an

inner and an outer telescoping section and a hinge connecting said pipes, a driving gear carried by said delivery pipe, a driven gear carried by said discharge pipe, said gears intermeshing when said hinge is 35 closed, and means operatively connecting said driven gear and said outer telescoping section adapted to project or retract said outer section with respect to said inner section when said driving gear is revolved. 40

2. In a pneumatic stacker comprising a delivery pipe, a discharge pipe having an inner and an outer telescoping section and a hinge connecting said pipes, a driving gear carried by said delivery pipe, means 45 for actuating said driving gear, a driven gear carried by said discharge pipe, said gears intermeshing when said hinge is closed, and means including a chain having a lug connected to said outer telescoping 50 section and an independently supported sprocket wheel, operatively connecting said driven gear and said outer telescoping section, adapted to project or retract said outer section with respect to said inner section 55 when said driving gear is revolved.

In testimony whereof, I affix my signature.

GEORGE WETTLAUFER.
